(57) **CLAIM**

The ornamental design for a fingerprint scanner, as shown and described.

DESCRIPTION

FIG. 1.1 is a perspective view of a fingerprint scanner according to my design.

FIG. 1.2 is a front view of the fingerprint scanner shown in FIG. 1.1.

FIG. 1.3 is a back view of the fingerprint scanner shown in FIG. 1.1.

FIG. 1.4 is a left view of the fingerprint scanner shown in FIG. 1.1.

FIG. 1.5 is a right view of the fingerprint scanner shown in FIG. 1.1.

FIG. 1.6 is a top view of the fingerprint scanner shown in FIG. 1.1.

FIG. 1.7 is a bottom view of the fingerprint scanner shown in FIG. 1.1.

The broken lines in the drawings disclose unclaimed portions of a USB hub only and form no part of the claimed design.
